UNITED STATES PATENT OFFICE.

WILLIAM C. DILLMAN, OF BROOKLYN, ASSIGNOR TO OWEN WALSH, OF NEW YORK, N. Y.

ANNUNCIATOR.

SPECIFICATION forming part of Letters Patent No. 472,439, dated April 5, 1892.

Application filed December 22, 1891. Serial No. 415,863. (No model.)

To all whom it may concern:

Be it known that I, WILLIAM C. DILLMAN, of Brooklyn, in the county of Kings and State of New York, have invented a new and Improved Annunciator, of which the following is a full, clear, and exact description.

My invention relates to improvements in that class of annunciators which are used in connection with speaking-tubes and which are operated by a current of air passing through the tubes, the purpose of the annunciator being to announce when a person is at one end of the tube and wishes to talk with the person at the opposite end.

15 The object of my invention is to produce an extremely simple annunciator of the character described which may be easily operated by the breath of a person blowing into the tube and which will operate in such a way 20 that the circuit through the electric bell will be closed momentarily only, and will thus prevent quick exhaustion of the battery.

To this end my invention consists in an annunciator the construction of which will be 25 hereinafter described and claimed.

Reference is to be had to the accompanying drawings, forming a part of this specification, in which similar figures and letters of reference indicate corresponding parts in both the 30 views.

Figure 1 is a broken vertical longitudinal section of the annunciator embodying my invention, showing also the electrical connections; and Fig. 2 is a cross-section on the line 35 2 2 in Fig. 1.

The speaking-tube 10 is of the usual kind and is supported at one end in the usual wall-board 11 and is closed at its mouth by a common form of swinging lid 12, which lid is hinged 40 to a face-plate 13, secured to the wall-board 11, having a flange 13^a to enter the mouth of the speaking-tube. The lid 12 has a bent arm 12^a on its back, which carries a latch 12^b at its lower end, and the latch swings upward when 45 the lid swings downward and engages a cross-piece 12^c, which thus prevents the lid from dropping too far. This construction is shown in the United States Patent No. 458,947, dated September 1, 1891, and forms no part of this 50 invention.

A hollow chamber 14 of an essentially tri-

angular shape is produced on the top of the speaking-tube near the mouth of the latter, and secured to an insulating-block 15^a on the top of the chamber is a contact-strip 15, which 55 forms one terminal of the electric circuit and which is bent downward so as to extend to a point a little above the tube. This contact 15 is adapted to be struck by a swinging contact-arm 16, which is arranged horizontally 60 beneath it, the said arm 16 being pivoted on a suitable support 17 and having its free end weighted, as shown at 18, so that it will normally drop away from the strip 15. The contact-arm 16 is held to swing in a slot 19 in the 65 vertical portion of the wall of the chamber, and the arm is provided beneath its pivot with a depending stud 20, which serves as an abutment for the fan 21, which fan is pivoted on the support 17 and hangs down into the speaking- 70 tube 10. It will thus be seen that the fan 21 may be swung freely backward in the tube and up into the chamber 14, as shown by dotted lines in Fig. 1; but if swung in the opposite direction it will contact with the stud 20 75 and raise the arm 16, so that the latter will contact with the strip 15 and close the electric circuit, as hereinafter described.

An electric bell 22 is arranged adjacent to the mouth of the tube in the usual way, and 80 the connections between the bell and the operative parts of the annunciator are as follows: A battery A, located in any convenient place, connects by a wire a with one of the binding-posts of the bell and also by a wire a² with 85 the contact-arm 16. The contact-strip 15 is also connected with one binding-post of the bell by a wire a'. It will thus be seen that when the two contacts 15 and 16 touch the circuit will be from the battery through the wire a, the bell 22, the wire a', the contacts 15 and 16, and the wire a² to the battery.

The speaking-tube and annunciator are especially adapted for use in connection with the common form of removably flexible mouth-tube, as shown by dotted lines in Fig. 1, and the operation of the device is as follows: When a person wishes to use the tube and desires to attract attention, he blows into the tube and the current of air strikes the fan 21, 90 raises the contact-arm 16, so that it touches the contact-strip 15, and the circuit through 95 100

the bell is thus closed and the bell rung; but as soon as the air ceases to act on the fan the contact-arm 16 will drop, thus breaking the circuit and preventing the disagreeable long-continued ringing of the bell and also saving the battery. When a person called comes to the tube, the usual flexible mouth-tube is thrust into the tube, as shown by dotted lines in Fig. 1, and this tube, striking the fan 21, 15 pushes it backward and upward in the main tube, thus throwing it out of the main passage, so that it will not in any way interfere with conversation.

I am aware that it is not new to close the circuit through an electric bell by means of air-operated mechanism carried by the tube, and I do not claim this feature, broadly, as my invention.

Having thus fully described my invention, I claim as new and desire to secure by Letters Patent—

1. The combination, with a speaking-tube, of a contact supported above the tube and forming one terminal of an electric-bell circuit, a swinging contact forming the other terminal of the bell-circuit and arranged beneath the upper contact and adapted to strike the same, and a fan connected with the swinging contact and extending into the bore of

30 the tube, substantially as described.

2. The combination, with the speaking-tube, of an upper contact fixed above the tube and forming one terminal of an electric-bell cir-

cuit, a contact-arm forming the other terminal of the circuit and held to swing against the upper contact, and a fan held to swing in the bore of the tube, said fan being adapted to swing freely in one direction and to raise the contact-arm when swung in the opposite direction, substantially as described.

3. The combination, with the speaking-tube, of a swinging contact-arm supported above the tube and forming one terminal of an electric-bell circuit, a depending stud produced on the arm near its pivoted end, a swinging fan mounted in the tube and arranged to swing against the stud, and a contact mounted in the path of the swinging contact and forming the other terminal of the bell-circuit, substantially as described.

4. The combination, with the speaking-tube, of a chamber produced on the upper part of the tube, a swinging contact-arm mounted in the chamber and held to swing in a slot of the chamber-wall, a fan pivoted in the chamber and extending into the bore of the tube, said fan being adapted to operate the swinging contact-arm, and a contact forming the other terminal of the bell-circuit, said contact being mounted in the chamber and extending into the path of the swinging contact, substantially as described.

WILLIAM C. DILLMAN.
